UNITED STATES PATENT OFFICE.

LUDWIG HECHINGER, OF ROCHESTER, NEW YORK.

GALVANIC PAD.

SPECIFICATION forming part of Letters Patent No. 252,765, dated January 24, 1882.

Application filed May 19, 1881. (No model.)

To all whom it may concern:

Be it known that I, LUDWIG HECHINGER, of Rochester, Monroe county, New York, have invented a certain new and useful Improvement 5 in Galvanic Pads; and I do hereby declare that the following is a full, clear, and exact description of the same, reference being had to the accompanying drawings, in which—

Figure 1 is a face elevation of the device. 10 Fig. 2 is a vertical cross-section of the same. Figs. 3 and 4 are face views of two of the separate metallic disks. Figs. 5 and 6 are cross-sections, respectively in lines *x x* and *y y*. Fig. 7 is a view of one of the clasps for holding the disks together.

My improvement relates to galvanic pads or appliances for application to the human body; and the invention consists in the construction and arrangement hereinafter more 20 fully described and definitely claimed.

The pad is constructed upon the well-known principle of the voltaic pile, consisting of several metallic disks of different kinds united in pairs, with layers of cloth or bibulous paper 25 interposed between the pairs for the purpose of receiving moisture to excite the galvanic action.

In the drawings, A B C, &c., represent the several disks of which the pad is composed, 30 the same being made of different metals and placed together in pairs, with disks of cloth or paper placed between the pairs for receiving moisture.

My improvement is as follows:

35 In the edges of the disks, at uniform distance apart, are made a series of notches or indentations, *d d d*, and near them are a series of holes, *f f f*, cut through the disks at a little distance from the edges, the notches and 40 holes coinciding.

g g are clasps made of thin flexible metal, and of the square or rectangular form shown in Fig. 7. When the disks are all in position the square closed ends of the clasps are placed 45 in the notches *d d*, and the loose ends of the clasps are inserted through the holes *f f*, embracing the edges of the disks, and the ends are then clasped in through the holes, as shown in Fig. 2.

50 By the means above described the disks are all fastened securely together, but can be readily separated by opening the clasps again,

enabling the parts to be arranged and replaced at pleasure. The clasps, by fitting in the notches *d*, prevent any turning or loose movement of the disks. The device is much cheaper, simpler, and more effective than screws.

In the interior metallic disks of the pad are cut longitudinal slots *a a a*, parallel to each other and at uniform distances apart, as shown 55 in Fig. 4. When two of these disks are placed in contact the two sets of slots are made to cross each other at right angles. By this means the moisture or the exciting-liquid is 60 enabled to pass into and through the slots and 65 come into intimate contact with all parts of the metal, thereby producing a better chemical action than where the disks are closed.

In the outer disks of the pile are made a series of corrugations or grooves, *b b*, extending nearly across the disks and corresponding with the slots *a a* in the other disks. When the disks are placed together the outer ones are so arranged that the grooves or corrugations *b b* stand crosswise of the slots in the 70 adjoining disks. These grooves or corrugations form cross-channels in the outer imperforate disks, and allow the exciting-fluid which enters the slots to flow in contact with the inner faces of the outer disks, which it would not 75 readily do if the faces of the disks were flat and laid close together.

Having thus described my invention, I claim—

1. In a galvanic pad, the combination of the 80 slotted disks provided with the square notches *d d d* in the outer edges and the holes *f f f* coincident therewith, and the thin metallic clasps *g g*, fitting flush in the notches and 85 clasped through the holes, as shown and described, and for the purpose specified.

2. In a galvanic pad, the combination of the interior disks provided with slots crossing at right angles, and the exterior disks imperforate and provided with corrugations or grooves 90 crossing the adjoining slots at right angles, as herein shown and described.

In witness whereof I have hereunto signed my name in the presence of two subscribing witnesses.

LUDWIG HECHINGER.

Witnesses:

R. F. OSGOOD,
R. E. WHITE.
